[57] CLAIM

The ornamental design for a holder for the suspension of a pair of collapsible toothpaste or shampoo tubes, as shown and described.

DESCRIPTION

FIG. 1 is a perspective view of a holder for the suspension of a pair of collapsible toothpaste or shampoo tubes showing our new design;

FIG. 2 is a left side elevational view thereof, the right side being a mirror image of that shown;

FIG. 3 is a front elevational view thereof;

FIG. 4 is a top plan view thereof;

FIG. 5 is a bottom plan view thereof; and

FIG. 6 is a rear elevational view thereof.

FIG. 1

FIG. 2

FIG. 3

FIG. 4

FIG. 5
